VERTICAL RETORT FOR THE CARBONIZATION OF COAL AND LIKE CARBONACEOUS MATERIALS

Frederick Joseph West and Ernest West, Miles Platting, Manchester, England, assignors to West's Gas Improvement Company Limited, Miles Platting, Manchester, England, a company of Great Britain

Application November 30, 1934, Serial No. 755,502
In Great Britain December 2, 1933

2 Claims. (Cl. 202—220)

This invention is an improvement in or modification of the invention described and claimed in Serial No. 701,198 filed 6th December 1933, and comprises an arrangement wherein the annular or ring like carbonization zone of the retort which forms an enclosure for the combustion zones within, is divided up by vertical partitions into a plurality of separate sections, each with its own charging and choke discharging means. The 5 vertical partitions may be continuations of the division walls between the combustion chambers and serve to transfer heat from the combustion chamber walls direct to the outer walls of the combustion zone and also to strengthen the 10 complete structure.

The coke discharge doors may be disposed at the base of each section of the carbonization zone or at the base of cooling and steaming zones below the carbonization zone. Such doors may 15 be hingedly mounted at the inner side of the annular carbonization zone so as to deliver the coke outwards.

Referring to the two accompanying sheets of explanatory drawings:—

25 Figure 1 is a sectional elevation,

Figure 2 a sectional plan on the line 2—2 of Figure 1,

Figure 3 a sectional plan view on the line 3—3 of Figure 1,

30 Figure 4 a sectional plan on the line 4—4 of Figure 1, and

Figure 5 a sectional plan on the line 5—5 of Figure 1 of a vertical retort unit constructed and arranged in one convenient form in accordance 35 with this invention. Figures 2 to 5 are drawn to a larger scale than Figure 1.

Figure 6 is an inverted plan view of part of the base of the retort shown in Figure 1, this view showing a discharge door for one of the retort 40 sections or divisions.

Figure 7 is a sectional side view on the line 7—7 of Figure 6.

Figure 8 is an end view looking in the direction of the arrow 8 in Figure 7.

45 The retort proper comprises the annular space divided into sections *a*, *b*, *c*, and *d*, by the division walls *e*, *f*, *g*, and *h* which are continuations of the division walls separating the combustion chamber sections *i*, *j*, *k*, and *m*. The centre boss like 50 portion *n* from which the division walls radiate ensures that the combustion gases which rise up the space *i*, *j*, *k*, and *m* are kept in intimate contact with the inner wall *o* of the retort proper or carbonizing sections. The gas for combustion 55 in the sections *i*, *j*, *k*, and *m* rises up the centre

passage *p* as shown by the arrow *p'*, to the flame orifices *q*, one for each section of the combustion space. Secondary air for combustion in the sections *i*, *j*, *k*, and *m* rises up the spaces *r* (see Figure 4) as shown by the arrow *r'* in Figure 1 to the orifices *s*. Dust pockets *t* are provided at the base of the combustion chamber sections. These pockets can be emptied at intervals by removing the closures *t'*.

5 Each section *a*, *b*, *c*, and *d* of the carbonizing space has its own discharge door at its lower end. Figures 6, 7, and 8 are detail views of a discharge door *u*. This is pivoted to the two arms *v* fulcrumed at *w* at the inner side of the carbonization space. A hanging catch *x* which may be 10 spring loaded serves to support the outer side of the door independently of the arms *v* which are engaged by hanging catches *y* carried by eccentric pivot pins with handles *z* thereon by which the door can be tightened against the lower end 15 of the retort.

20 Each section *a*, *b*, *c*, and *d* of the carbonization space is charged separately from a hopper or chute *10* supplied from a common coal bunker or hopper *11* by way of valve or damper controlled 25 passages *12*. *13* indicates compartments for containing coke breeze which can be fed into the hoppers *10* by valve or damper controlled passages *14*. As will be seen by reference to Figure 3, slides *15* are provided to control the passages 30 *12* and *14*, each slide controlling two passages so that coal and coke cannot be fed simultaneously to the hopper *10*. The coke is fed into a retort section after it has been discharged so as to cover the discharge door *u* at the base thereof. The 35 fuel supply inlet to each section *a*, *b*, *c*, *d* of the annular carbonization chamber is controlled by a damper plate *16*, see Figure 5, one damper plate being shown clear of the feed opening *17* of a carbonization or retort section.

40 The coal during carbonization passes downwards through the part-annular sections *a*, *b*, *c* and *d* as shown by the arrow *a'*. The walls of these sections *a*, *b*, *c*, *d* diverge gently apart from one another from top to bottom of the retort.

45 The four gas-offtakes of the four sections *a*, *b*, *c*, and *d* are shown at *18* in Figure 5. They lead to two collecting mains *19* which connect up to the foul main *20*. The burning gases pass up the combustion chamber sections as shown by the arrow *j'* and the waste gases from the top of the combustion chamber sections *i*, *j*, *k*, and *m* pass 50 into a common space *21* and so to the waste gas flue *22* as shown by the arrow *22a*.

55 The carbonization sections *a*, *b*, *c*, and *d* form

along with the division walls *e*, *f*, *g*, and *h* a complete enclosure for the combustion chamber sections and no external heat is applied to the outer wall 23 of the retort or carbonization sections. We thereby reduce radiation losses and increase fuel economy and efficiency. The walls *e*, *f*, *g*, and *h* form heat conductors from the combustion chambers to divide up the carbonization space so that a section of such space can if desired be charged 10 whilst another is being discharged or a section can be kept out of service temporarily. The walls or divisions *e*, *f*, *g*, and *h* also strengthen the structure against distortion.

The coke discharge means may be varied as 15 shown in our prior application previously referred to.

If desired one chute 10 may serve to charge all 20 the sections of the annular retort, such chute being mounted for movement around the top of the retort.

We claim:

1. A vertical retort for the carbonization of coal or the like comprising a vertical combustion chamber, an annular carbonization chamber 25 forming a complete peripheral enclosure for the said combustion chamber and bounded on its outer side by the outer wall of the retort, the said outer wall being free from external heating means, and a series of radial partitions extending from a central hub within the said combustion chamber to the outer wall of the retort and dividing said combustion chamber and annular carbonization chamber into sections, together with means to supply combustible and secondary air to each of 30 said sections of said combustion chamber and to remove flue dust at the base thereof and to withdraw products of combustion therefrom centrally above the top of said annular carbonization chamber, separate but co-related means to supply ma-

terial to be carbonized or alternatively protective material such as coke breeze to each of said sections of said annular carbonization chamber, means to withdraw carbonized material from the bottom of each carbonization chamber and to withdraw gaseous products of carbonization from the top thereof, each of said carbonization chamber sections having continuous, unbroken walls which diverge radially apart from top to bottom of the section. 10

2. A bank of vertical retorts for the carbonization of coal or the like comprising a vertical cylinder split up by radial partitions into a plurality of sectors each constituting a retort, each of the said sectors comprising in order from the centre 15 radially outwards a hub of fire resisting material, a single combustion chamber, a wall in the form of a portion of an annulus bounding said combustion chamber, a single carbonization chamber in the form of a segment of an annulus, and an outer wall in the form of a portion of an annulus 20 free from external heating means, the said two walls diverging one from another from top to bottom of said carbonization chamber, the said combustion chamber being furnished with means for supply of combustible and secondary air and for removal of flue dust at the base thereof and for removal of products of combustion at the top thereof at a point above the upper end of the carbonization chamber, a single hopper to contain 25 material to be carbonized, a second hopper to contain coke breeze or like material, means to place either of said hoppers in connection with the top of each retort to feed material thereto, means to withdraw carbonized material from the bottom 30 of said retort and means to remove gaseous products of carbonization from the top of said retort. 35
